CORK CUTTING MACHINE

John M. Binder, New Hyde Park, N. Y., assignor
to Consolidated Cork Corporation, New York,
N. Y., a corporation of New York

Application September 28, 1939, Serial No. 296,888

15 Claims. (Cl. 144—21)

This invention relates to machines for cutting cork rods into disks, such as are employed as packings in the metal caps used as closures for bottles, cans and similar receptacles.

5 In the manufacture of these disk-like cork packings, ground or comminuted cork is pressed into lengthy rods and these rods are placed vertically in a rotating turret. As the turret rotates, the rods are carried thereby into contact with a 10 rotating cutting knife which severs the rods into the disks. The rods to be severed are carried by the rotating turret in vertically disposed tubes, there being a weight located in each tube to bear down upon the top of the rod therein to constantly force the rod downwardly toward the 15 bottom of the turret and toward the rotating knife located thereat and at the same time to prevent rotative movement of the cork rod within the tube. Since the turret is provided with a 20 relatively large number of the tubes within which the cork rods are placed, and since a separate weight is employed in each tube, the task of removing these weights and replacing them each time the tubes must be refilled with cork rods, is 25 a tedious and time-consuming one.

Accordingly, the primary object of the present invention is to provide a cork-cutting machine wherein all of the weights employed for the purpose of exerting downward pressure upon the cork rods, will be controlled as a unit, whereby all of the weights may be unitarily raised when the tubes require refilling with cork rods and then unitarily lowered and brought to rest upon the top of the cork rods within the tubes.

35 Another object of the invention is to provide a weight-raising and lowering means of the character described wherein means are provided by which a plurality of weights may be raised or lowered simultaneously, yet said weights will have 40 independent descending movement to thereby rest with equality of pressure upon all of the cork rods into the tubes regardless of variation in the length of the rods.

These and other objects are accomplished by 45 the invention, a more particular description of which appears hereinafter and is set forth in the claims appended hereto.

In the accompanying drawings, forming a part 50 hereof, Fig. 1 is a side elevation of a cork-cutting machine made in accordance with the invention; Fig. 2 is a sectional view on the line 2—2 of Fig. 1, looking in the direction of the arrows; Fig. 3 is a plan view of the machine; Fig. 4 is a sectional view through one of the tubes for holding the 55 cork rod to be cut into disks; Fig. 5 is a sec-

tional view on the line 5—5 of Fig. 4, looking in the direction of the arrows; Fig. 6 is a sectional view on the line 6—6 of Fig. 3, looking in the direction of the arrows; Fig. 7 is a sectional view on the line 7—7 of Fig. 6, looking in the direction of the arrows; and Fig. 8 is a sectional view on the line 8—8 of Fig. 7, looking in the direction of the arrows.

In the drawings, 1 indicates a top or table portion of a supporting frame which includes the side bars 1a and legs 2, the latter resting upon the floor or other suitable support. The main drive shaft is indicated at 3, the same being rotatably mounted in the bearings 4 and 5 on the frame, said shaft having a pulley 6 secured upon it and another pulley 7 loose on it. A belt 8 extends from a suitable source of power such as an electric motor, and said belt extends around either the pulley 6 or the pulley 7, said belt being shifted from one pulley to the other by means of the shifter-fingers 9 provided on the longitudinally movable control shaft 10. It will be understood from the foregoing that when the belt is extended around the loose pulley 7, shaft 3 will not be rotated and when the belt has been shifted to extend around the pulley 6, the shaft 3 will then be driven. The means for shifting the control shaft 10 to secure drive or non-drive of shaft 3 will be later described.

Shaft 3 carries a beveled gear 11 which meshes with beveled gear 12 secured on the end of a vertical shaft 13 extending through bearing 14 formed on the top 1 of the frame of the machine. At its upper end, the vertical shaft 13 is secured in a boss 15 formed on a rotatable turret 16. The turret is formed with annular walls 17 and 18 and anchored between said walls is a plurality of vertically-disposed tubes 19, each of said tubes being adapted to receive a cork rod 20 intended to be cut into disks as the turret is rotated by means of a revolving disk cutter 21 (see Fig. 1). Cutter 21 is secured on shaft 105 carrying pulley 106 engaged by belt 107 extending from a suitable source of power.

The bottom of the turret 16 is apertured below 45 each tube 19 to permit the cork rod to descend and project out of the lower end of the turret as shown at 22 in Fig. 4, this projecting portion of each rod coming into contact with the cutter 21 and being severed to produce a disk. An annular plate 23 limits the downward movement of the cork rod and determines the thickness of the disk to be severed from the cork rod by the disk cutter 21. The turret elements thus far de- 50 55

scribed are old and well known in this art and form no part of the present invention.

To facilitate the placement of a cork rod in the tubes 19, each of said tubes is formed with a cut-away portion 24 or opening, clearly disclosed in Figs. 1 and 4. In placing the rod in position in the tube, the rod may be flexed slightly as indicated in dotted lines in Fig. 4 and is slid downwardly into the tube in the manner indicated by the dotted lines and arrow in said figure. The cork rod 20 in each tube is adapted to be forced downwardly and also held against rotative movement within the tube in which it is placed by means of a weight 25 located in each tube. Each weight is capable of gravitational descent independently of the other weights. The lower end of each weight 25 is provided with teeth 26 which engage the top of the cork rod in the tube 19 and prevent the same from rotative movement. Surrounding the outside of each tube 19 is a collar 27 which is pinned to the weight 25 within the tube by means of a pin 28 extending through the collar 27 and entering into the weight 25. Each of the tubes 19 is provided with an elongated slot 29 through which the pin extends and which permits raising and lowering movement of the weight 25, collar 27 and pin 28 as a unit.

The upper ends of the gang of tubes 19 are held in an annulus 30 provided with three inwardly bent arms 31 engaging the upper ends of three guide rods 32, the lower ends of said rods being threaded or otherwise fixed in bosses 33 formed on the turret 16, as shown in Fig. 2. These three guide rods 32 constitute vertical guiding means for the radial arms 34 of a spider 35. The radial arms 34 of the spider carry a lifter ring 35a which, when the spider 35 is elevated, engages under the projecting portions of pins 28 on all of the weights 25, and simultaneously raises all of the weights. The spider is suspended upon a cable 36. At one end the cable engages loop 37 secured to a ball-bearing 38 mounted in the hub portion 39 of the spider so that while the spider can rotate freely with the turret 16, the cable and bearing 38 will remain stationary during such rotative movement of the spider, turret, and various tubes 19 carried thereby. The cable 36 extends over spaced pulleys 40 and 41 rotatably mounted on an angle-iron 42 forming a cross bar extending over the top of the turret and supported at the upper ends of the vertical rods 43 and 44. Cable 36 is attached to a counter-balance weight 45 which is guided vertically through an opening 46 (see Fig. 6) in guide member 47 secured upon the supporting rod 44.

The lower end of weight 45 is attached to cable 49 (Fig. 6) which extends downwardly through a slotted guide member 50 secured on the frame 60 of the machine, and is secured to a pulley 51, loose on a shaft 52. Shaft 52 is rotatively mounted in the bearings 53 and 54 fastened to the underside of the top 1 of the frame of the machine. Secured on shaft 52 is a beveled gear 55 which is driven by a beveled gear 56 secured on vertical shaft 13.

Loose on shaft 52 and attached to pulley 51 is a ratchet 57, adapted for engagement at certain times by a pawl 58 pivoted at 59 on the frame of the machine, the pawl being of bell-crank formation and having a projecting arm 60 engaged by spring 61 tending to force the pawl into engagement with the ratchet 57.

Shaft 10, on which the belt-shifting fingers 9

are secured, is movable through guide 62, the longitudinal movement of said shaft through said guide being limited by the stop pin 63 projecting from shaft 10 and movable within the limits of the slot 64 formed in the guide 62. The shaft 10 is also longitudinally movable through a bracket 65 secured to the side of the machine frame by the bolts 66. A block 67 is fastened on shaft 10 by pin 68, said block supporting a rod 69 which extends parallel to the shaft and is slideable through the machine frame and has a pointed or tapered end 70 which enables the rod to slide beneath the arm 60 of the pawl 58 to lift said arm, as shown in Fig. 6, and cause disengagement of the pawl with the ratchet 57 and hold the pawl in such disengaged position. This occurs at a time when the spider 35 is being elevated and the lifter ring 35a thereof is simultaneously raising all of the weights 25. A coil spring 71 surrounds shaft 10 and has one end bearing against the block 67 and its other end exerting pressure against the frame 1 of the machine. A manipulating handle 72 is secured on the end of the shaft 10.

Secured on the shaft 52 and therefore rotatable therewith, but keyed to slide longitudinally of said shaft, is a clutch member 73, said clutch member being provided with a dog 74 adapted to engage the dog 75 carried by the pulley 51 so that it will be apparent that when the clutch member is moved toward the pulley 51 to cause engagement of dogs 74 and 75, the pulley 51 and the ratchet 57 carried thereby, will be rotated with the shaft 52. Clutch member 73 is moved to engaged position by means of a yoke arm 76, said yoke arm being pivoted to the frame 1 at 77, the yoke arm being shifted by means of a hand lever 78, pivoted at 79 between lugs 80 extending from the frame member 1a. Near its upper end, the hand lever carries a roller 81 adapted to be engaged by the lower, smaller-diameter portion 82 of the balance weight 45 when said weight has descended so that its portion 82 has entered into the guide member 50. Guide member 50 is slotted as at 83, so that when the clutch member 73 is in its engaged position, as in Fig. 8, and the weight is being pulled down, the roller 81 will partially project through said slot and be disposed in the path of the portion 82 of the weight. Thus when the weight descends as the spider 35 reaches its elevated position to lift all of the weights 25, the portion 82 will, when the weight 45 reaches the limit of its descending movement, enter into guide 50 and act as a cam against the periphery of the roller 81 to force the same outwardly to thereby also shift hand lever 78 to the right as viewed in Figs. 7 and 8, and thereby disengage clutch member 73 from driving engagement with the pulley 51. Pulley 51 thereupon stops rotation and the upward movement of the spider 35, lifter ring 35a and all of the weights 25 ceases. A spring 85 bears against the periphery of the pulley 51 and acts as a friction brake.

Pivoted at 86 to the upright rod 44 is a lever 87, the upper end portion of which is formed with slot 88 in which a stop pin 89 projecting from rod 44 is located, to thereby limit the extent of rocking movement of the lever. At its upper end, lever 87 is provided with a cam surface 90 adapted to be engaged by the larger-diameter part 91 of the counter-balance weight 45 when said weight descends. A leaf spring 92 secured on the rod 44 presses against the lever 87 above its pivot 86, thereby normally holding said lever in the position 76

shown in full lines in Fig. 6, so that the lower end portion 93 of said lever engages a notch 94 provided in shaft 10, thereby holding said shaft in the position where it maintains belt 8 on the driving pulley 6 to thereby keep the turret 16 in rotation.

Briefly, the operation of the machine is as follows:

In its position of rest, at which time the turret 16 is in a non-rotating condition, the spider 35 is in an elevated position, and its lifter ring 35a is engaged under the pins 28 and has raised the weights 25 above the cut-out portions 24 in tubes 19, as shown in Fig. 4, enabling the cork rods 20 to be inserted one after another into all of the tubes 19. At this time, pawl 59 is in engagement with the ratchet 57 preventing said ratchet from turning in a direction to permit the descent of the spider under its own weight. At this time 20 also, spring 71 is exerting its influence on shaft 10 so that the belt-shifter fingers 9 have moved the belt to position on the loose roller 7, whereby shaft 3, and the gearing driven thereby is idle. Also at this time, counter-balance weight 45 is in 25 a lowered position with its portion 82 bearing against roller 81 and holding clutch member 73 in a disengaged position.

When all of the tubes 19 in the turret have been filled with cork rods 20, the operator pulls on lever 72, toward the left as viewed in Fig. 2, and against the tension of the spring 71. When this is done belt 8 is moved from loose pulley 7 to the pulley 6 and shaft 3 begins to rotate, to thereupon rotate the turret 16. As the shaft 10 is moved longitudinally under manual pull and is held in a drawn-out position until weight 45 has risen to a position above the upper end of lever 81, rod 69 carried by said shaft, engages under arm 60 of the pawl 59 and disengages the pawl from ratchet 57 as shown in Fig. 6. When the pawl is disengaged from the ratchet 57, the ratchet and attached pulley 51 are free to rotate on shaft 52 so that the spider 35, lifter ring 35a and all of the weights 25 are free to descend of their own weight, the spider coming to rest on the supports 99 on turret 16 and the weights 25 coming to rest upon the tops of the cork rods in the tubes 19. As the turret is rotated, the lower end of the cork rods are brought into contact with the disk cutter 21 in the manner well understood and the rods are severed into the cork disks which fall into the chute 100 and into a suitable receptacle placed below the chute.

When all of the cork rods have been severed into disks, rotation of the turret is stopped to permit the tubes 19 to be refilled with cork rods. To do this, the operator pushes lever 78 inwardly, or toward the right as viewed in Fig. 2, causing clutch member 73 to be engaged with pulley 51. Upon pulley 51 being so rotated, it begins to wind up cable 49, drawing counter-balance weight 45 downwardly and exerting pull on cable 39 to cause it to raise the spider 35. As spider 35 rises, its lifter ring 35a engages underneath projecting portions of the pins 28 and lifts all of the weights 25 simultaneously to a position above each of the cut-out portions or openings 24 in the tubes 19 (Fig. 4). As weight 45 descends, its larger-diameter portion 91 operates against the cam portion 90 of lever 87 to swing said lever as indicated in dotted lines in Fig. 6 and move the lower end 93 of said lever out of the notch 94 in shaft 10. When this takes place, spring 71 thrusts shaft 10 longitudinally toward the right, as viewed in Fig. 2, to cause belt-shifter fingers 9 to move the belt

3 from roller 6 onto loose roller 7 and thereupon stop rotation of the shaft 3 and the turret 16 driven therefrom.

As shaft 10 is moved longitudinally under the impulse of spring 71, rod 69 is moved from its position beneath arm 60 of pawl 59 so that the pawl is brought into engagement with the ratchet 57. As weight 45 continues its descent, its smaller-diameter portion 82 enters into guide 50, contacts with roller 81 and forces lever 78 outwardly or 10 into disengaged position. Rotation of the turret 16 has ceased, pulley 51 has stopped its rotation, weight 45 is in the lowered position shown at c in Fig. 6, the spider is elevated and all of the weights 25 are held in raised position by the 15 lifter ring 35a. The operator now fills the tubes 19 with cork rods 20, pulls on handle 72 and holds the same pulled out against the tension of spring 71 until the weight 45 has passed upward beyond the cam portion 90 of the lever 87. Operator then 20 allows end 93 of lever 87 to enter the notch 94 of shaft 10. The parts are now in the positions shown in Fig. 2, the turret is rotating, and the rods are being severed into the disks.

It will be seen from the foregoing that while 25 an arrangement is provided by means of which all of the weights 25 may be simultaneously raised and lowered, the mechanism which raises the weights and permits them to be lowered is such as to permit each weight to have freedom 30 of movement, independent of the others. That is to say, since each weight can come down on top of the cork rod located below it in the tube independently of the other weights, each weight can adjust itself to any variation in the length 35 of the rods placed in the tubes. Thus, all of the advantages of freely independent weights is secured by the improved construction, yet at the same time all of the weights can be manipulated simultaneously and a great saving in time is thus 40 provided.

What I claim is:

1. In a machine for cutting cork rods into disks, a rotating turret provided with a plurality of tubes, each of which receives a cork rod to be severed into disks, a rotary cutting knife to which the rods are successively carried by rotation of the turret, a weight contained within each tube for exerting downward pressure upon the rod therein, and means for simultaneously raising all of the weights to an elevated position in the tubes or simultaneously lowering all of the same within the tubes.

2. In a machine for cutting cork rods into disks, a rotating turret provided with a plurality of vertically-disposed tubes, each of which receives and carries a cork rod to be severed into disks, a rotary cutting knife to which the rods are carried by rotation of the turret, a weight contained within each tube above the cork rod 50 therein for exerting downward pressure upon the rod, and means for simultaneously raising all of the weights out of the portions of the tubes wherein the rods are located or simultaneously bringing all of the weights to rest upon 55 the upper ends of the rods within the tubes, said means permitting independent downward pressure of each weight.

3. In a machine for cutting cork rods into disks, a rotating turret provided with a plurality of vertically disposed tubes, each of which receives and holds a cork rod to be severed, a weight in each tube for exerting pressure on the upper end of the cork rod in the tube, each of said weights having a projecting element extend- 75

ing externally of the tube, an annular lifter for engaging said projecting elements to lift said weights, means for engaging said lifter to cause the same to be rotated with the turret, and means for raising and lowering said lifter to cause the same to raise all of the weights into the upper portion of the tubes within which they are contained, and to cause lowering movement of all of the weights simultaneously when the lifter is lowered.

4. In a machine for cutting cork rods into disks, a rotating turret provided with a plurality of vertically disposed tubes, each of which receives and holds a cork rod to be severed, said tubes being arranged in circular formation, a weight in each tube for exerting pressure on the upper end of the cork rod in the tube, each of said weights having a projecting element extending externally of the tube, an annular lifter arranged within the circle of tubes for engaging with the projecting elements on all of the weights to thereby lift all of said weights simultaneously or permit simultaneous lowering movement of the same when said lifter is lowered, and means for raising and lowering said lifter.

5. In a machine for cutting cork rods into disks, a rotating turret provided with a plurality of vertically disposed tubes, each of which received and holds a cork rod to be severed, said tubes being arranged in circular formation, a weight mounted for vertical sliding movement within each tube to exert pressure on the upper end of the cork rod in the tube, a collar mounted for sliding movement on the outside of each tube, a pin extending through the collar and tube and entering the weight, the tube having an elongated slot to permit vertical movement of the pin, an annular lifter arranged within the circle of tubes for engaging with the projecting pins on all of the weights to thereby lift all of the weights simultaneously or permit simultaneous lowering movement of all of said weights when said lifter descends, and means for raising and lowering said lifter.

6. In a machine for cutting cork rods into disks, a rotating turret having a plurality of tubes arranged in a circle, a weight mounted for vertical movement in each tube, an annular lifter within the circle of tubes, said lifter being rotatable with the turret, means on the weights for engaging said lifter when the lifter is elevated to cause simultaneous raising movement of all of the weights within the tubes, and non-rotative means for raising and lowering the lifter.

5. In a machine for cutting cork rods into disks, a rotating turret provided with a plurality of vertically disposed tubes, each of which receives and holds a cork rod to be severed, said tubes being arranged in circular formation, a weight mounted for vertical sliding movement within each tube to exert pressure on the upper end of the cork rod in the tube, a collar mounted for sliding movement on the outside of each tube, a pin extending through the collar and tube and entering the weight, the tube having an elongated slot to permit vertical movement of the pin, an annular lifter arranged within the circle of tubes for engaging with the projecting pins on all of the weights to thereby lift all of the weights simultaneously or permit simultaneous lowering movement of all of said weights when said lifter descends, means on the turret for guiding the lifter in its raising and lowering movement and causing rotation of said lifter in company with the turret, and means for raising and

lowering said lifter, said raising and lowering means being stationary with respect to the turret.

8. In a machine for cutting cork rods into disks, a rotating turret having a plurality of vertically disposed tubes arranged in a circle, a weight vertically movable in each tube, an annular lifter rotatable with the turret and located within the circle of tubes, means on the weights extending in a direction toward the center of the circle of tubes for engaging said lifter when the lifter is elevated to cause simultaneous raising movement of all of the weights within the tubes, and non-rotative means for raising and lowering the lifter.

9. In a machine for cutting cork rods into disks, a rotating turret having a plurality of vertically disposed tubes arranged in a circle, a weight vertically movable in each tube, each of said tubes being provided with an elongated slot, a pin extending from each weight and extending through the slot and projecting outside of the tube, a vertically movable lifter member located below the projecting portions of the pins and adapted on its upward movement to engage said pins and simultaneously raise all of the weights, raising and lowering mechanism for said lifter member, said raising and lowering mechanism being fixed relative to the rotating turret.

10. In a machine for cutting cork rods into disks, a rotating turret provided with a plurality of tubes, each of said tubes receiving a cork rod to be severed into disks, a rotary cutting knife to which the rods are successively carried by rotation of the turret, a weight contained within each tube for exerting downward pressure upon the cork rod therein, an annular lifter member for raising all of the weights simultaneously within the tubes, means on the turret for guiding said lifter member in its raising and lowering movement, means for raising and lowering the lifter member including a cable, pulleys over which said cable extends, a balance weight attached to said cable, a take-up pulley for winding up the cable to raise the lifter member, means for rotating said take-up pulley, said means including a clutch, and means controlled by the balance weight for disengaging the clutch when the lifter member has been elevated to the limit of its raising movement.

11. In a machine for cutting cork rods into disks, a rotating turret having a series of tubes arranged in a circle, a weight located in each tube, an annular lifter member disposed within the circle of tubes for engagement with all of the weights to lift the same simultaneously when the lifter member is raised, means for raising and lowering the lifter member, said means including a bearing permitting rotative movement of the lifter member in company with the turret while the raising and lowering means remains stationary.

12. In a machine for cutting cork rods into disks, a rotating turret provided with a series of vertical tubes, each of said tubes receiving a cork rod to be severed into disks, a rotary cutting knife to which the rods are successively carried by rotation of the turret, a weight contained within each tube for exerting downward pressure upon the rod therein, the weights being downwardly movable independently of one another, an annular lifter member surrounded by the series of tubes for raising all of the weights simultaneously within the tubes, means on the turret for guiding said lifter member in its rais-

ing and lowering movement, means for raising and lowering the lifter member including a cable, pulleys over which said cable extends, a balance weight attached to said cable, a take-up pulley for winding up the cable to raise the lifter member, means for rotating said take-up pulley, said means including a clutch, means controlled by the balance weight for disengaging the clutch when the lifter member has been elevated to the limit of its raising movement, and means also controlled by said balance weight for stopping rotation of the turret as the lifter member is rising.

13. In a machine for cutting cork rods into disks, a rotating turret having a series of tubes arranged in a circle, a weight located in each tube, an annular lifter member disposed within the circle of tubes for engagement with all of the weights to lift the same simultaneously when the lifter member is raised, means for raising and lowering the lifter member, said means including a cable, pulleys over which the same is moved, and a bearing suspended from the cable and carrying the lifter member, said bearing permitting rotative movement of the lifter member in company with the turret while the raising and lowering means remains stationary.

14. In a machine for cutting cork rods into disks, a rotating turret, a series of circularly arranged, vertical tubes carried thereby for receiving cork rods, a weight in each tube for exerting downward pressure upon each rod, a spider located within the circle of tubes, means for vertically guiding the spider, said guide means in-

cluding vertically disposed rods carried by the turret, an annulus carried by the spider, projections extending from the weights and overlying the annulus whereby raising movement of the spider will cause the annulus to engage the projections and elevate the weights within the tubes, and means for raising and lowering the spider, said means including a bearing whereby the spider can rotate thereon in company with the turret and independently of the raising and lowering means.

15. In a machine for cutting cork rods into disks, a rotating turret, a series of circularly arranged, vertical tubes carried thereby for receiving cork rods, a weight in each tube for exerting downward pressure upon each rod, a spider located within the circle of tubes, means for vertically guiding the spider, said guide means including vertically disposed rods carried by the turret and extending through the arms of the spider, an annulus carried by the spider, projections extending from the weights and overlying the annulus whereby raising movement of the spider will bring the annulus into engagement with the projections and elevate the weights within the tubes, and means for raising and lowering the spider, said means including a cable and means for exerting pull thereon, and a bearing suspended on said cable whereby the spider can rotate on said bearing in company with the turret and independently of the raising and lowering means.

JOHN M. BINDER.
